DESIGN FOR A CLOCK

Jacob L. Bazelon, Chicago, Ill.

Application July 31, 1940, Serial No. 94,059

Term of patent 7 years

To all whom it may concern:

Be it known that I, Jacob L. Bazelon, a citizen of the United States, residing at Chicago, in the county of Cook and State of Illinois, have invented a new, original, and ornamental Design for a Clock, of which the following is a specification, reference being had to the accompanying drawing, forming part thereof.

Figure 1 is a front elevation of the clock embodying my new design.

Fig. 2 is a side elevation thereof.

I claim:

The ornamental design for a clock, as shown.

JACOB L. BAZELON.
